UNITED STATES PATENT OFFICE.

CHARLES H. CROWELL, OF BROOKLYN, NEW YORK.

NONPILFERING SHIPPING CONTAINER.

Application filed November 13, 1920. Serial No. 423,839.

To all whom it may concern:

Be it known that I, CHARLES H. CROWELL, a citizen of the United States, and resident of the borough of Brooklyn, county of 5 Kings, city and State of New York, have made a certain new and useful Invention relating to Nonpilfering Shipping Containers, of which the following is a specification, taken in connection with the accompanying 10 drawing.

This invention relates especially to shipping containers made up of flat shipping composite paper board, if desired. This composite paper board preferably comprises 15 outer facing sheets and one or more intermediate or central connector sheets which may in some cases be joined and held apart to form the cellular composite paper board by embossed corrugated or other irregular 20 spacing sheets adhesively or otherwise secured in place. When such central or intermediate connector sheets are used the paper board may be conveniently and effectively formed with rabbeted or stepped edges so 25 that one or more of the container sides having such stepped edges may interlock with the adjacent edges of the other blank so as to ensure a much stronger and more rigid connection. In some cases these stepped 30 interlocking edges of the container blanks may be adhesively secured together as by the use of a non-pilfering holding strip of double 35 gummed tape which may be moistened on both sides and then laid or arranged in the joint between the stepped edges of the blanks so as to become adhesively secured to both and strongly hold them together.

In the accompanying drawings showing in a somewhat diagrammatic way several illustrative embodiments of the invention.

Fig. 1 is a perspective view of one form of the container shown partly in section.

Fig. 2 is an enlarged transverse section of the material taken along the line 2—2 of 45 Fig. 1; and

Fig. 3 is a perspective view showing a modified form of container.

The container shown in Fig. 1 comprises two similar blanks of nearly the same size 50 dependent on the thickness of stock used, each of which is formed with transverse folding creases so as to fold up into three adjacent sides of the container. One blank may thus form the sides 1, 2 and 3 of the container while the other similar though somewhat larger blank may be folded up so

as to form the sides 4, 5 and 6. These container blanks which are of course preferably shipped in flat form may advantageously be formed in the factory with stepped portions or in some cases with stepped or rabbeted edges throughout their entire periphery so as to secure the added strength and security of definite interlocking edged portions at all the junction corners of the container. A 65 suitable composite paper board for use in this connection is shown somewhat diagrammatically in Fig. 2, as comprising the outer facing sheets 11, 13 and the central connector sheet 12 of any suitable paper or pulp material, these sheets being adhesively or otherwise joined to intermediate embossed or other facing sheets of paper 9, 10 which serve to hold the outer facing sheets in position and produce a strong cellular paper board. Any suitable form of bosses, projections, ribs or other irregular surface shapes may be used in these spacing sheets although round or other outwardly projecting 70 bosses give good results and the bosses 75 may be arranged to project in opposite direction in substantial alignment which is described in somewhat greater detail in the applicant's co-pending case Serial No. 410,178, filed September 14, 1920. Such composite paper board may be formed with rabbeted or stepped edges around some or all of the edges of the container blanks so that 80 as shown in Fig. 1, the projecting edge 15 of one blank may have its central connector sheet rest upon the reduced thickness outer edge of the cooperating outer blank forming the side 2 of the container. Both of these container blanks may be formed with folding creases such as 14 so that when they have 85 been shipped to the user's factory the flat sized blanks may be folded up preferably around a suitable form or support so as to 90 form the three adjacent sides of the container such as 4, 5 and 6, then the other cooperating blank may be put in place and the holding means such for instance as the double gummed holding strips 7, which may in 95 some cases be preliminarily attached to one edge of one of these blanks which may be moistened on both sides and then arranged within the stepped joint or seam between the blank edges, the outer edges of these holding strips being then forced or smoothed down over the edges of the other blank as is 100 shown quite clearly at the left lower corner of Fig. 1. In this way a strong adhesively 105

110

secured joint is formed between the blank edges which may if desired be further strengthened by applying an additional sealing strip such as 8 over the outside edge of the joint which also covers the exposed gummed edge of this sealing strip. The non-pilfering sealing strip may for this purpose be advantageously made by gumming on both sides a relatively thin strong paper stock such as twenty or thirty pound Kraft paper and for convenience in shipping one edge of this strip 7 may be pasted around the edges of one of these container blanks if desired. In some cases these non-pilfering strips may be printed or formed with a distinctive pattern or design so as to further minimize their being replaced by other strips in resealing an opened container. Also in some cases it is desirable to use penetrating aniline coloring material such as aniline violet, methylene blue, etc. in the special printed lines 25 or other design incorporated in the gummed coating on these sealing strips, since such aniline coloring is to some extent transferred to the adjacent faces of the container in connection with the moistening and applying of the holding strips, so that even similar non-pilfering gummed strip would leave a different or superimposed impression which would at once show that the container had been previously opened.

The similar form of container blanks illustrated in Fig. 1 are quite desirable and when such stepped joints are used produce sufficiently strong containers with a considerable saving of the paper board material as compared with the standard construction now used. It is not however necessary in all cases to use such interchangeable or similar shaped blanks and Fig. 3 shows another construction in which one of the blanks comprises the two relatively small sides of the container while the other larger blank forms the three larger sides 19, 20 and 21. These blanks may of course be similarly creased to form the folding creases 29 and if desired similar double gummed holding strips 22 may be used in the stepped joints formed by the edges of these container blanks, outer sealing strips such as 23 being also employed in some cases if desired. It is of course understood that these stepped joints may be formed with any suitable adhesive or other fastening means and for example the stepped edges may have glue, gum or other adhesives directly applied thereto before they are forced into place and the outer sealing strips such as 23 may be used in connection with such a construction.

This invention has been described in connection with a number of illustrative embodiments, forms, portions, parts, materials, arrangements and methods of manufacture

and use, to the details of which disclosure 65 the invention is not of course to be limited, since what is claimed as new and what is desired to be secured by Letters Patent is set forth in the appended claims.

1. The paper board shipping container 70 having joints formed by the edges of the different blanks and double gummed non-pilfering holding strips formed with a distinctive transferable design comprising aniline coloring matter in the gum coatings thereon 75 arranged between the edges of said blanks and adhesively secured thereto.

2. The paper board shipping container 80 having joints formed by the edges of the different blanks and gummed non-pilfering holding strips formed with a distinctive transferable design comprising coloring matter in the gum coatings thereon arranged in engagement with the edges of said blanks 85 and adhesively secured thereto.

3. The paper board shipping container 90 having joints formed by the edges of the different blanks and non-pilfering holding strips formed with a distinctive transferable design comprising aniline coloring matter 95 thereon adhesively secured to the cooperating edges of said blanks.

4. The paper board shipping container 95 having joints formed by the edges of the different blanks and non-pilfering holding strips formed with a distinctive transferable design thereon adhesively secured to the cooperating parts of said blanks.

5. The paper board shipping container 100 having stepped joints formed by the interlocking edges of the different blanks and double gummed non-pilfering holding strips formed with a distinctive transferable design comprising aniline coloring matter in the gum coatings thereon arranged between the interlocking edges of said blanks and adhesively secured thereto. 105

6. The paper board shipping container 110 having stepped joints formed by the interlocking edges of the different blanks and double gummed non-pilfering holding strips formed with a distinctive design arranged between the interlocking edges of said blanks and adhesively secured thereto.

7. The paper board shipping container 115 having joints formed by the edges of the different blanks and double gummed non-pilfering holding strips formed with a distinctive design adhesively secured to the cooperating edges of said blanks. 120

8. The paper board shipping container 125 having joints formed by the edges of the different blanks and a non-pilfering holding strip formed with a distinctive design on the face which is adhesively secured to the cooperating edges of said blanks.

CHARLES H. CROWELL.
